Dec. 368

John Abendroth of Port Chester, N. Y.
Letters Patent No. 368 - Dated April 15, 1851.

The Schedule, referred to in these Letters Patent, and making part of the same.

To all whom it may concern:

Be it known

that I, John Abendroth of Port Chester, in the County of West Chester and State of New York, have invented a new and useful

Design for Small Cooking Stoves;

And I do hereby declare that the following is a full and exact description of the same, reference being had to the accompanying drawings, forming part of this specification, in which

Fig. 1 is a plan, or top view of the stove.

Fig. 2 is a plan of the bottom plate.

Fig. 3 is a front elevation and

Fig. 4 is a side elevation of the stove complete.

Fig. 5 is a profile section of one side of the body and edge of the top plate.

Fig. 6 is a profile section of the front edge of the bottom plate.

Similar letters of reference indicate corresponding parts in the several figs.

The top plate A, whose form is shown in Fig. 1, is surrounded, except at the part where the chimney seat joins it, with a moulding a, of the form of an inverted ovolu - See Figs. 1 4 and 5.

The bottom plate B, is surrounded, except at the part where the draught plate fits, with an ornamental leaf and flower border, as represented at b. Fig. 2; Around the front part surrounding the draught plate, is an ogee seen at c. Fig. 2 and 6.

The body of the stove C, and the sides

of the flue fort D are ornamented close under the top plate by a band of leaves d, between every two of which appears a drop e- these are best seen in Fig. 3.

The feet E, E, are ornamented with scroll work- their pattern is shown in Figs. 3 and 4.

The draught plate F has an ornamental border f, representing strands of rope, a cord, - See fig. 2.

What I claim as my invention and desire to secure by Letters Patent, is

The design, configuration and arrangement of the ornaments on the several parts of the Cooking Stove, as herein represented and described.
